(57) **CLAIM**

The ornamental design for an indoor plant cultivator, as shown and described.

DESCRIPTION

FIG. 1 is a front perspective view of the indoor plant cultivator showing our new design; FIG. 2 is a front view thereof; FIG. 3 is a back view thereof; FIG. 4 is a left side view thereof; FIG. 5 is a right side view thereof; FIG. 6 is a top plan view thereof; FIG. 7 is a bottom plan view thereof; FIG. 8 is a bottom perspective view thereof; FIG. 9 is an exploded perspective view with the water tank separated; FIG. 10 is a perspective view of the indoor plant cultivator shown in an environment of use with a broken line seed kit; and, FIG. 11 is an exploded perspective view with the extension pipes separated.

The broken lines depict portions of the indoor plant cultivator that form no part of the claimed design. The broken lines in FIG. 10 showing a seed kit show environmental structure only and form no part of the claimed design.

1 Claim, 11 Drawing Sheets
